UNITED STATES PATENT OFFICE.

FREEBORN F. RAYMOND, 2d, OF NEWTON, MASSACHUSETTS, ASSIGNOR, BY MESNE ASSIGNMENTS, TO THE MCKAY SHOE MACHINERY COMPANY, OF MAINE.

HEEL-NAILING MACHINE.

SPECIFICATION forming part of Letters Patent No. 624,538, dated May 9, 1899.

Application filed February 4, 1890. Serial No. 339,166. (No model.)

To all whom it may concern:

Be it known that I, FREEBORN F. RAYMOND, 2d, a citizen of the United States, residing at Newton, in the county of Middlesex and State 5 of Massachusetts, have invented a new and useful Improvement in Heel-Nailing Machines, of which the following is a full, clear, and exact description, reference being had to the accompanying drawings, forming a part 10 of this specification, in explaining its nature.

The invention is an improvement upon that described in my application for Letters Patent of the United States filed April 16, 1887, Serial No. 234,985; and it comprises various 15 details of organization and construction whereby the machine is simplified and the time of its operation quickened.

In the drawings, Figure 1 is a view in front elevation of a machine having the features of 20 my invention. Fig. 2 is a view in vertical central section taken from front to rear of the machine. Fig. 3 is a detail view, principally in plan, to illustrate the top-lift-spanking plate and cam for operating the same. Fig. 25 4 is a view of the top-lift-spanking plate inverted to show the top-lift holder upon its under side.

A is the cross-head. It has a downward-extending projection a, in which is a cross-30 dovetail a' to receive a dovetail tongue a² on a driver-holding block a³. a⁴ represents the gang of drivers. The head A is vertically movable in the guides a⁵ a⁶, bolted to the frame A'.

35 B is the main shaft of the machine. It is connected by pinions b with the crank-gears b' on the shaft b². Each gear b' has a crank-pin b³, and the crank-pins are connected with the cross-head A by the connecting-rods b⁴.

40 The shaft b² is supported by suitable bearing or pillow blocks and has a pressure-cam C.

c is a vertically-sliding pressure-head having an extensible or adjustable top c' and an antifriction-roll c², which bears on the pres-45 sure-cam C.

D is the jack. d is the spindle carried thereby and which when the jack is in position rests upon the pressure-head. It supports the last or work-support d'.

50 E is the templet-plate. It is adjustable or removable from the table e.

E' is the nail-carrier.

e' is the nail-carrier slide, to which the nail-carrier is secured. The slide has a cam-pin e², entering a cam-groove e³ in the cam e⁴ on 55 the vertical shaft e⁵.

F is a top-lift-spanking plate. It has secured upon its under surface a top-lift-holding device comprising the breast-holders f' and the back-holder f². This spanking-plate 60 is at the forward end of a lever f³, which is pivoted at f⁴, and has a cam-pin f⁵ entering a cam-groove f⁶ in the cam-disk f⁷ upon the vertical shaft e⁵. The vertical shaft e⁵ has one revolution for every reciprocation of the 65 cross-head A. The vertical shaft e⁵ is shown in Figs. 1 and 2, principally in Fig. 2, as connected with the shaft b² by means of a gear e⁶ upon the shaft e⁷, which gear meshes with one of the gears b' and is of the same size. 70 The shaft e⁷ has the bevel-gear e⁸, which engages the bevel-gear e⁹ at the lower end of the vertical shaft e⁵. Consequently the shaft e⁷ and the vertical shaft e⁵ are given the same rate of rotation as the shaft b², and the cams 75 e⁸, f⁷, and C rotate at the same speed. The pressure-cam C has one revolution for every reciprocation of the cross-head A.

The start and stop motion mechanism may be like that described in the application of C. 80 C. Small, filed November 8, 1889, Serial No. 329,696, excepting that it is arranged to stop the machine after each reciprocation of the cross-head and preferably when the head is about a third of its stroke down. 85

Any other equivalent start and stop motion mechanism may be employed. The head A is given sufficient extent of stroke or movement to provide sufficient time for the movement of the nail-carrier E' into and out of 90 operative position. The pressure-cam C is timed or constructed first upon the starting of the machine to immediately move the pressure-head and therefore the last or work-support upward to forcibly or otherwise compress 95 the boot or shoe heel or other work it carries against the under surface of the templet E, and this movement is completed before the nails are caused to be driven into the heel or work. The cam then holds the pressure-head, last, and work in this position during 100 the driving of the nails, and then immediately

permits the quick downward movement or descent or fall of the pressure-head and work, this downward movement of the pressure-head being facilitated by the springs C. 5 This downward movement is immediately followed by another quick upward movement without rest, upward movement, and downward movement, there being no appreciable rest between the last upward and downward 10 movements. The machine then stops. It will be seen that the first downward, second upward, and downward movements take place during the movement of the cross-head from its lowest position to just beyond its highest 15 position when at rest. Upon the first downward movement of the pressure-head and work the top-lift-spanking plate F, carrying the top lift, if it is desired to blind-nail the top lift, is moved rapidly into position from 20 one side of the boot or shoe or work-support over it, the cam f^7 being constructed to provide the plate with this movement and also to hold it there for an instant during the second upward movement of the pressure-head 25 and work until the pressure-head and work have fallen slightly or sufficiently to permit the reverse movement of the top-lift-spanking plate and its return to its original position. The top lifts may be placed in the top-lift holder by hand or fed thereto by a feed-plate moved automatically or by hand. The nail-carrier E' is immediately moved forward upon the starting of the machine and comes 30 into position to deliver its nails to the holes of the templet before the drivers enter its holes, and upon the upward movement of the cross-head immediately after the ends of the drivers clear or leave its holes its operating-cam moves it backward to a position to be 35 filled with nails. The nails preferably are fed to it by automatic nail distributing and feeding devices similar to those described in various of my patents. The cross-head A is moved downward upon the starting of the 40 machine, the drivers entering the holes of the nail-carrier and templet, driving the nails into the work, and then upward to its highest position, and then slightly downward, when the machine comes to rest. By giving the cross- 45 head A sufficient throw, and by mounting the pressure-cam C upon the crank-shaft, and by constructing it as described, and by giving the vertical shaft e^5 one revolution for every reciprocation of the cross-head, I am enabled 50 to employ cams which will permit the parts to be moved as above specified, and to obtain very easy cams, and to well apply the power from the driving-shaft, and to very much simplify the construction of the machine as compared with that shown and described in the application referred to. 55 It will be understood, of course, that in this machine the heel-blank or work is not pricked, but for certain classes of work it is not necessary that the heel-blank or work be previously pricked. Of course this mechanism 60

can be used for any kind of work to which gang-nailing is applicable.

It will thus be seen that the machine herein described embraces in a complete organization means so combined and operated that by one revolution of a shaft the heel-blank is compressed, the attaching-nails driven, the top lift fed and attached, and the parts separated to permit the removal of the finished boot or shoe from the machine. It will further be noticed that to accomplish this result it is necessary that the last or work-support, templet or pressure-plate, and drivers should be, when the machine is at rest, held separated from each other to permit the shoe to be placed upon the last and the heel to be placed between the shoe and the templet, and also to permit the nails, unless they have been previously placed in the heel-blank, to be fed to the templet. 75 80 85

Upon the starting of the machine its first action is to compress the heel-blank between the last or work-support and templet or pressure-plate and to drive the attaching-nails. 90 This is followed by the separation of the last or work-support with the work thereon and the templet or pressure-plate and the introduction of the top-lift holding and spanking plate or top-lift-spanking plate between them, 95 and this in turn is followed by another compressing action between the last or work-support and templet, and this again is followed by the separation of these two parts, so that during the complete action of the machine, 100 or, in other words, during the rotation of the actuating-shaft, one engagement of the templet with the drivers and two engagements or impacts between the last or work-support and the templet have taken place. This organization is especially valuable in heel-nailing machines, because it simplifies the construction of such machines and increases their capacity. 105

Having thus fully described my invention, 110 I claim and desire to secure by Letters Patent of the United States—

1. In a heel-nailing machine, a reciprocating cross-head carrying heel-attaching devices, a templet or pressure-plate, a last or work-support, a cam on the crank-shaft for giving the latter two impacts and periods of separation during one revolution of the shaft, and a top-lift plate and mechanism for moving it between the templet or pressure-head 115 and the work when separated substantially as described.

2. In a heel-nailing machine, a reciprocating cross-head carrying a gang of drivers, a templet or pressure-plate, a last or work-support, a cam on the crank-shaft for giving the latter two impacts and periods of separation during one revolution of the shaft and a top-lift plate having top-lift-holding devices and mechanism for bringing it between the templet or pressure-head and the work, when separated, substantially as described. 125 130

3. In a heel-attaching machine, a reciprocating cross-head carrying heel-attaching devices, a templet or pressure-plate, a nail-carrier, a last or work-support, a cam on the 5 crank-shaft for giving the latter two impacts and periods of separation during one revolution of the shaft, a top-lift carrier, and mechanism for moving it between the templet or pressure-head and the work when separated, 10 substantially as described.

4. The combination in a nailing-machine of a reciprocating cross-head A, a gang of drivers carried thereby, the shaft B, the pinions b thereon, the shaft b^2 , the gears b^3 carried thereby to mesh with the pinions b, the crank-pins b^3 on the gears b^3 , the rods b^4 connecting the 15 cross-head with the crank-pins, the templet, the last or work-support, carried upon a vertically-movable spindle d, a vertically-movable 20 pressure-head on which said spindle rests, a cam C upon the shaft b^2 constructed to impart two forcing movements to the pressure-head, jack-spindle, and last or work-support each full rotation, the shaft e^5 , the 25 nail-carrier slide e' , the nail-carrier E', the operating-cam e^4 , as and for the purposes described.

5. The combination in a nailing-machine of a reciprocating head A, a gang of drivers carried thereby, the shaft B, pinions b carried thereby, the cam-shaft b^2 , the gears carried thereby to mesh with the pinions b, the pressure-cam C, constructed as specified, carried by the shaft b^2 , crank-pins b^3 on the gears b^3 , 30 the rods b^4 connecting the crank-pins with the cross-head, the pressure-head c, actuated by the cam C, the jack having a slide-spindle to rest upon the pressure-head and bearing a last or work-support, the templet, a spanker-plate with or without a top-lift holder, its lever f^3 , an operating-cam upon the vertical 35 shaft e^5 , the said vertical shaft e^5 , the nail-carrier E', its operating-cam e^4 , all combined to operate as and for the purposes described.

45 6. In a heel-nailing machine, a reciprocating cross-head carrying nail-driving devices, a templet or pressure-plate, a last or work-support and a crank-shaft connected to the cross-head for imparting to it a single reciprocation, and a cam on the crank-shaft for imparting to the last or work-support two impacts during one reciprocation of the cross-head, as set forth.

7. In a heel-nailing machine, in combination 50 with a templet or pressure-plate, a gang of nail-driving devices on one side thereof and means for imparting one reciprocation thereof toward and from said templet, and a last or

work-support on the opposite side of said templet, and means for moving said last or work-support toward and from the templet or pressure-plate twice during the said single reciprocation of the gang of nail-driving devices, all as set forth. 60

8. In a heel-nailing machine, in combination with a stationary templet or pressure-plate, a gang of nail-driving devices on one side thereof, and means for imparting thereto a single reciprocation toward and from said templet, and a last or work-support on the 70 opposite side of said templet and means for moving said last or work-support toward and from the templet or pressure-plate twice during the said single reciprocation of the nail-driving devices, all as set forth. 75

9. In a heel-nailing machine, the combination of a templet or pressure-plate, a gang of nail-driving devices on one side thereof, means for imparting thereto a single reciprocation toward and from said templet, a top-lift 80 spanker on the opposite side of said templet and means for moving it into and out of operative position, a last or work-support also upon the opposite side of said templet, and means for moving said last or work-support 85 toward the templet in advance of the driving of the nails, and for holding it stationary during the driving of the nails, and for moving it from the templet or pressure-plate after the driving of the nails and for then moving it 90 toward and from the top-lift spanker, all during a single reciprocation of the nail-driving devices, as and for the purposes set forth.

10. In a heel-nailing machine, in combination with a templet or pressure-plate, a gang 95 of nail-driving devices on one side thereof and means for imparting thereto one reciprocation toward and from said templet, a top-lift spanker on the opposite side of said templet, means for moving it into and out of operative 100 position, and a cam for supporting said last or work-support constructed to move said last or work-support toward the templet or pressure-plate in advance of the driving of the 105 nails and to hold it stationary during the driving of the nails, and to then permit the movement of the last or work-support from the templet, and to then move the last or work-support to the top-lift spanker and permit its movement from the spanker all in one reciprocation of the nail-driving devices, as set forth. 110
